ELECTROMAGNETIC PUMPING APPARATUS

Frederick R. Farrow, Jr., Audubon, and Edgar B. Nichols, Moorestown, N. J., assignors to Nichols Products Company, Moorestown, N. J., a corporation of New Jersey

Application August 20, 1938, Serial No. 225,886

1 Claim. (Cl. 103—53)

This invention relates to electromagnetic pumping apparatus and more particularly to apparatus for pumping gaseous fluids from a suitable source to an analyzing instrument.

Pumping apparatus of this type generally includes a membranous driving element which is reciprocated under the influence of electromagnetic impulses to force the gas from a suitable inlet, through the pump, and out through a suitable outlet, the passage of the gas through the pump being controlled by valve structure associated with the pumping element. In most pumps of this type, as heretofore constructed, the valves are mounted on the pumping element itself, and this presents certain disadvantages from a practical standpoint.

The primary object of our invention is to provide an improved pump of the type set forth which will be free from disadvantages characteristic of prior art pumps.

More particularly, it is an object of our invention to provide an improved pump as aforesaid which will have a long life and will be free from leakage.

Another object of our invention is to provide an improved pump which may be operated at relatively high speed.

Still another object of our invention is to provide an improved pump as aforesaid in which the valves will operate in accurate synchronism with the reciprocating pumping member.

A further object of our invention is to provide an improved pump of the type described in which the driving force may be readily adjusted.

Still a further object of our invention is to provide improved valve structure for pumps of the type under consideration.

Another object of our invention is to provide, in a pump of the type described, a pumping member which is self-restoring so as not to require extraneous means for restoring this member when the motive power is removed.

It is also an object of our invention to provide an improved pump which is quiet in operation, which is highly efficient in operation, and which is inexpensive to manufacture.

In accordance with our invention, we provide a pump with a valve plate in spaced relation to a thin membranous pumping member, preferably of stainless steel, the pumping member being held against the valve plate by a clamping ring. The valve plate is provided with a pair of spaced ports with each of which is associated a valve comprising a thin strip of mica one end of which is fixed to the valve plate and the other

end of which extends over and covers the associated port, a phosphor bronze spring bearing against the valves to hold them in port closed position. The pumping member has secured thereto a soft iron pole piece, and the clamping ring carries a bridge on which is adjustably mounted an electromagnet which, when energized by alternating current, serves to attract the pole piece with the frequency of the alternations to vibrate the pumping member correspondingly and thereby draw in the fluid through the inlet port and force it out of the exhaust port to suitable analyzing apparatus or the like. A bracket carried by the clamping ring has a set screw threaded therein for determining the position of the electromagnet on the bridge. Moreover, the membranous pumping member is either cupped away from the electromagnet or is stiffened at its center by the addition of a suitable stiffening washer so that it will be constantly biased to assume a position away from the electromagnetic actuating means.

The novel features that we consider characteristic of our invention are set forth with particularity in the appended claim. The invention itself, however, both as to its organization and method of operation, together with additional objects and advantages thereof, will best be understood from the following description, when read in connection with the accompanying drawing, in which—

Figure 1 is an elevation of one form of pump according to my invention,

Figure 2 is a sectional view thereof taken on the line II—II of Fig. 1, and

Figure 3 is a plan view of a modified form of driving member.

Referring more particularly to the drawing wherein similar reference characters designate corresponding parts throughout, we have shown a valve plate 1 provided with an inlet port 3 and an outlet port 5, both of which extend therethrough. The valve plate 1 is provided with a flange 7 between which and a clamping ring 9, a thin membranous pumping member 11 is clamped, a pair of gaskets 13 being disposed on each side of the pumping member 11 between the flange 7 and clamping member 9, and a plurality of screws 15 preferably holding the parts in assembled relation. The pumping member 11 is preferably cupped away from the valve plate 1 for a purpose presently to be set forth.

Fixed at one end thereof to the inner surface of the valve plate 1 is a valve 17 formed of a thin strip of mica, silk or the like, having its free end

extending over the inlet port 3, a phosphor bronze spring 18 constantly tending to hold the valve 17 in closed position over the port 3. A similar valve 21 is fixed at one of its ends to the outer surface of the valve plate 1 and is arranged to cover the outlet port 5 under the influence of a phosphor bronze spring 23. When the valve 17 is in open position, gas or other fluid may be drawn into the collecting chamber 25 through an inlet tube 27, and when the valve 21 is opened, the gas or fluid may be forced through the port 5 into an expansion chamber 29 formed by a cup 31 from which an outlet tube 33 extends.

To effect opening and closing of the valves 17 and 21, which are, of course, oppositely disposed, as will be clearly seen from Fig. 2, we provide the pumping member 11 with a pole piece 35 which is arranged to be attracted by an electromagnet 37 having a connection to a source of alternating current supply. The electromagnet 37 is adjustably mounted on a bridge 39 formed on the clamping ring 8, and is secured in adjusted position by means of a screw 41. The clamping ring 8 also has secured thereto a bracket 43 in which is threadedly received an adjusting screw 45 against which the electromagnet 37 may be set. Thus, by loosening the screw 41, adjusting the set screw 45 and moving the electromagnetic structure 37 up against the screw 45, the air gap between the pole piece 35 and the electromagnet 37 may be readily adjusted whereby the attractive force between the electromagnet 37 and the armature or pole piece 35 may be pre-set.

Upon passing an alternating current through the coil of the electromagnet 37, the electromagnet will be energized at the frequency of the current source. This will correspondingly attract the pumping member 11 to permit the gas entering the tube 27 under pressure to force open the valve 17 and enter the collecting chamber 25. At each alternation of the current supplied to the electromagnet 37, the member 11 will automatically assume its original position as shown in Fig. 2 to close the valve 17 and open the valve 21, whereupon the collected gas will be forced through the port 5 and into the expansion chamber 29, after which it will pass out through the tube 33. The cupped or dished member 11 not only provides an arrangement 50 for automatically resetting the pumping mem-

ber to its normal position, but serves also to counteract the D. C. component of the electromagnetic system by reason of its great, inherent restoring force.

5 In Fig. 3, we have shown the pumping member 11 provided with a stiffening washer 47 on the surface thereof opposite that to which the pole piece 35 is secured. This serves to stiffen the pumping member 11 centrally and has the same 10 function as dishing or cupping the pumping member.

From the foregoing description, it will be apparent that we have provided a very simple, inexpensive, and efficient electromagnetic pump for feeding fluids from a suitable source to a suitable destination. The arrangement of the valves in a valve plate separate and part from the diaphragm 11 itself has the great advantage of making the valves self-cleaning. This is especially valuable where the pump is used for pumping liquids, flue gases, or the like. Although we have shown and described but one embodiment of our invention, it will be apparent to those skilled in the art that many modifications 20 thereof and changes therein are possible within the spirit of our invention. We therefore desire that our invention shall not be limited except insofar as is made necessary by the prior art and by the spirit of the appended claim.

30 We claim as our invention:

In fluid pumping apparatus, the combination of a valve plate, a membranous pumping member associated with said valve plate in spaced relation thereto and cooperating therewith to 35 provide a fluid collecting chamber, said valve plate having an inlet port and an outlet port formed therein, valve means associated with each of said ports and arranged to work in opposite direction, said valve means comprising flat mica strips each having one end fixed to said valve plate and arranged to have the other end cover its associated port, spring means constantly urging said strips into position to cover said ports, means providing a fluid expansion chamber associated with said outlet port, and electromagnetic means for actuating said pumping member, said electromagnetic means being adjustable relative to said pumping member.
